UNITED STATES PATENT OFFICE

HERBERT V. HENDERSON, OF DETROIT, MICHIGAN, ASSIGNOR TO CHRYSLER CORPORATION, OF DETROIT, MICHIGAN, A CORPORATION OF DELAWARE

DESIGN FOR A ROBE RAIL

Application filed June 15, 1929. Serial No. 31,708. Term of patent 3½ years.

To all whom it may concern:

Be it known that I, HERBERT V. HENDERSON, a citizen of the United States, residing in the city of Detroit, county of Wayne, and State of Michigan, have invented a new, original, and ornamental Design for Robe Rails, of which the following is a specification, reference being had to the accompanying drawings, forming a part thereof, in which:

Fig. 1 is a plan view of a robe rail.

Fig. 2 is a view corresponding to Fig. 1,

showing the central portion of the robe rail broken away, the end portions being enlarged.

Fig. 3 is a side elevation of one end of the robe rail, as viewed on line 3—3 of Fig. 2.

The dominant feature of the design consists in the intermediate configuration and the surface ornamentation shown in Fig. 3.

I claim:

The ornamental design for a robe rail substantially as shown and described.

HERBERT V. HENDERSON.
